UNITED STATES PATENT OFFICE.

WILLIAM C. WINFIELD, OF WARREN, OHIO, ASSIGNOR TO THE WINFIELD MANUFACTURING COMPANY, OF SAME PLACE.

DESIGN FOR A BAIL-EAR.

SPECIFICATION forming part of Design No. 22,236, dated February 21, 1893.

Application filed January 3, 1893. Serial No. 457,167. Term of patent 7 years.

To all whom it may concern:

Be it known that I, WILLIAM C. WINFIELD, a citizen of the United States, residing at Warren, in the county of Trumbull and State of Ohio, have invented and produced a new and original Design for Ears to Secure Bails on Cans and the Like, of which the following is a specification, reference being had to the accompanying drawings, forming a part thereof.

Figure 1 is a front elevation of an ear showing my design. Fig. 2 is a cross section of Fig. 1, on line x , x , thereof. Fig. 3 is a perspective view.

15 A represents the surface of the substantially semi-spherical center portion of my new design in ears for the bails of cans, pails

and other vessels. The said surface A is convex, as shown, and the base about said portion A has a flat surface B. In the center of the semi-spherical portion of the said ear is a hole a , and beneath said hole is a depression, groove or channel b , terminating above in said hole a and feathering or running out on the surface A, substantially as shown.

Having thus described my invention, what I claim as new, and desire to secure by Letters Patent, is—

The design for a bail ear as herein shown and described.

WILLIAM C. WINFIELD.
